Inventors

UNITED STATES PATENT OFFICE.

ALBERT SICKAFOOSE AND WILLIAM EDWARD WYATT, OF LYONS, IOWA.

VALVE.

SPECIFICATION forming part of Letters Patent No. 579,186, dated March 23, 1897.

Application filed March 17, 1896. Serial No. 583,564. (No model.)

To all whom it may concern:

Be it known that we, ALBERT SICKAFOOSE and WILLIAM EDWARD WYATT, citizens of the United States, residing at Lyons, in the 5 county of Clinton and State of Iowa, have invented a new and useful Valve, of which the following is a specification.

Our invention relates to valves designed particularly for use in connection with a 10 steam-feed cylinder for sawmill-carriages which support logs during the sawing operation, and also adapted for use in connection with steam-pump cylinders and steam-engine cylinders, the object in view being to provide 15 a steam-tight balanced valve requiring the minimum throw to accomplish its adjustment to feed and exhaust the motive agent.

Further objects and advantages of this invention will appear in the following description, and the novel features thereof will be 20 particularly pointed out in the appended claims.

In the drawings, Figure 1 is a front view, partly in section, of a feed-cylinder apparatus embodying valves constructed in accordance with our invention. Fig. 2 is a longitudinal section of the improved valve. Fig. 3 is a transverse section of the same. Fig. 4 is a detail view of the bushing detached. Fig. 30 5 is a detail view in perspective of the means for connecting twin valves for simultaneous operation.

Similar numerals of reference indicate corresponding parts in all the figures of the drawings.

We have shown the valve embodying our invention in connection with a steam-feed cylinder 1 of the ordinary construction, and a valve 2 is arranged in communication with 40 each end of the cylinder for admitting steam to communicate motion in opposite directions to the piston 3.

The improved valve embodies a cylindrical casing 4, open at both ends and provided at 45 diametrically opposite points with steam-ports 5 and 6 and also at diametrically opposite points with cylinder and exhaust ports 7 and 8, the exhaust-port being branched, as shown at 8^a and 8^b. The casing is thickened, 50 as shown at 9, contiguous to and covering each port and is provided with an interiorly-threaded collar 10 for the reception of a pipe.

Branches 11^a and 11^b of the steam-supply pipe 11 are threaded in the openings communicating with the steam-ports 5 and 6. A connecting-pipe 12 is threaded into the opening 55 communicating with the cylinder-port 7, and also is arranged in communication with the cylinder, and an exhaust-pipe 13 is threaded into the opening communicating with the 60 branched exhaust-port 8.

A cylindrical bushing 14 is tightly fitted in the bore of the cylindrical casing, the same being preferably forced to place by hydraulic pressure, and this bushing is provided with steam-ports 15 and 16, a cylinder-port 17, and exhaust-ports 18, registering, respectively, with the corresponding ports in the casing and of less width than said ports in the casing. The ports in the casing are made 70 of greater width than required for the admission and exhaust of the motive agent, whereby in fitting new bushings to the casing any slight variation in the disposition of the ports in the bushing will not render the 75 device inoperative by partly closing and thus obstructing the openings.

The improved valve further embodies a rotary plug 19, preferably cast solid and subsequently bored and longitudinally slotted, 80 as shown at 20, to form a plurality of gates 21, adapted to close the ports in the bushing. The object in employing a branched exhaust-port resides in the fact that the branches thereof may be closed and opened with the 85 same throw or movement of the plug as the steam-ports, while the capacity of the exhaust-port is double that of each steam-port. The cylinder-port is permanently open, and the movement of the plug in opposite directions alternately opens and closes the steam and exhaust ports, the steam-ports being open when the exhaust-ports are closed, and vice versa.

The bushing is open at both ends and is 90 equal in length with the casing, and the bore of the bushing is tapered continuously from one end to the other to receive the exteriorly-tapered or conical plug, which is of greater length than the casing, whereby adjustment 100 of the plug may be accomplished to compensate for wear of the seat or inner surface of the bushing. The means which we employ for holding the valve-plug at the de-

sired adjustment to allow easy movement and at the same time prevent leakage of steam embody an axial shaft or spindle 22, fixed in the ends of the plug and projecting beyond the extremities thereof, as shown clearly in Fig. 2. The ends of the spindle are provided with center-bearings 23, in which are seated center-points 24, formed upon the inner extremities of set-screws 25, said set-screws being threaded in axial guides 26, carried by brackets 27, bolted to the extremities of the casing. When the surface of the valve-plug or bushing becomes worn sufficiently to allow leakage, both plug and seat may be ground by the usual application of emery and oil and a continuous rotary movement of the plug, after which the plug may be adjusted and secured in the desired position by means of the center-points. When the parts become worn to such an extent as to prevent further adjustment, a new bushing may be applied, and as the cost of a bushing is less than that of a plug it will be seen that the valve may be repaired and rendered practically as efficient as when new without the expense incident to the repair of valves of the ordinary construction.

The ports, both in the bushing which forms the valve-seat and in the plug, are elongated parallel with the axis of the valve (see Fig. 2) to make them of the requisite capacity with the minimum width in order to provide for the reversal of the passage of fluid through the valve or the alternate opening of the exhaust and steam ports with the minimum throw of the plug.

Various means may be employed for communicating the necessary rocking movement to the plug, according to the kind of cylinder in connection with which the valve is used, but when the valve is employed in connection with steam-feed cylinders, as illustrated in Fig. 1, an operating or sawyer's lever 28 is rigidly secured to one of the extensions of the plug-spindle 22, and is provided at intervals with center sockets or bearings 29, arranged in pairs upon opposite sides of the lever and spaced from the axis of the spindle to correspond with similar center sockets or bearings upon a corresponding lever of the co-operating valve at the opposite end of the steam-feed cylinder. A connecting-rod 30 is arranged between said levers and is provided at its extremities with adjustable center-points 31 to engage said opposite center sockets or bearings, whereby the movement of one of the operating or sawyer's levers communicates motion simultaneously to the valve-plugs. The adjustable connection between the rod 30 and the levers provides for changing the relative movement between the operating-lever 28 and the valves.

It is obvious that when used in connection with pumps or steam-engine cylinders the valve embodying our invention may be operated by means of eccentric or other valve-

gear forming no part of our present invention and being well known to those skilled in the art.

The bushing is counterbored, as shown at 32, between the ports therein in order to reduce the wearing of the plug and facilitate grinding and lubrication, lubricating material being supplied by means of oil-cups 33, located, respectively, at the ends of the casing and communicating with oil-holes 34, formed in the casing and arranged in registration with similar holes in the bushing.

Various changes in the form, proportion, and the minor details of construction may be resorted to without departing from the spirit or sacrificing any of the advantages of this invention.

Having described our invention, what we claim is—

1. A valve having a cylindrical casing provided in its seat with a lateral cylinder-port and a plurality each of steam and exhaust ports elongated parallel with the axis of the casing, the exhaust-port being branched with its arms deflected inwardly to tap the seat at intervals, and the steam and exhaust ports being of less width than the cylinder-port, and a rotary plug seated in the casing and provided with alternate elongated openings and gates arranged parallel with the axis of the plug, the division of the steam and exhaust ports providing for the reversal of the passage of fluid through the valve by the minimum movement of the plug, substantially as specified.

2. A valve having an open-ended cylindrical casing, an open-ended bushing removably fitted in the bore of the casing and having its bore tapered longitudinally to form a seat, said bushing and casing having registering steam, cylinder and exhaust ports of which those in the bushing are elongated parallel with the axis of the casing, a hollow plug fitted in said seat and provided with longitudinal slots or openings and intervening gates to cover said ports, said plug being longitudinally tapered, and means for holding the plug at the desired adjustment to compensate for wear, substantially as specified.

3. A valve having a casing provided with opposite steam-ports and opposite cylinder and exhaust ports, the exhaust-port being branched with its arms deflected inwardly to tap the bore of the casing at intervals, an open-ended slotted bushing fitted in the casing and having ports registering, respectively, with the steam and cylinder ports of the casing and with the branches of the exhaust-port therein, and a hollow rotary plug fitted in the bore of the bushing and provided with openings and intervening gates to close said ports, substantially as specified.

4. In a valve, the combination with a casing having a tapered open-ended seat and lateral ports, of a hollow rotary plug fitted in said seat and provided with corresponding lateral ports, a spindle fixed axially to the

plug and extending beyond the extremities thereof, threaded guides supported by brackets secured to the extremities of the casing, and center-points having threaded shanks 5 mounted in said guides and engaging center sockets or bearings in the extremities of the spindle, substantially as specified.

5. The combination with twin valves having rotary plugs, operating-levers secured to the plugs and provided with pairs of opposite center sockets or bearings located at different distances from the axes of the plugs, and a connecting-rod provided at its extremities

with opposite adjustable center-points to engage said center bearings or sockets whereby 15 the extent of relative movement of the connected valves may be varied to secure proper co-operation, substantially as specified.

In testimony that we claim the foregoing as our own we have hereto affixed our signatures 20 in the presence of two witnesses.

ALBERT SICKAFOOSE.

WILLIAM EDWARD WYATT.
